UNITED STATES PATENT OFFICE.

JOHN ANGELL, OF ST. LOUIS, MISSOURI.

STEAM-SEPARATOR.

SPECIFICATION forming part of Letters Patent No. 710,655, dated October 7, 1902.

Application filed April 24, 1901. Renewed February 3, 1902. Serial No. 92,314. (No model.)

To all whom it may concern:

Be it known that I, JOHN ANGELL, a citizen of the United States of America, and a resident of St. Louis, in the State of Missouri, 5 have invented certain new and useful Improvements in Steam-Separators, of which the following is a specification.

This invention relates to that type of separators for removing oil, water or condensation, &c., from steam and in which the steam is given a circuitous course through the apparatus to assist in such separation.

The present improvement has for its object to provide a simple and effective formation 15 and arrangement of parts adapted to effect and maintain an efficient separation of the water and oil from the passing steam, all as will hereinafter more fully appear and be more particularly pointed out in the claims. 20 I attain such object by the construction and arrangement of parts illustrated in the accompanying drawings, in which—

Figure 1 is a central vertical sectional elevation of a steam-separator embodying the 25 present invention; Fig. 2, a plan view of the same with the upper head or closure-cap removed.

Similar numerals of reference indicate like parts in both views.

30 Referring to the drawings, 1 represents the main separator-casing, composed of a cylindrical body portion and top and bottom heads or closure-caps 2 and 3 of a substantially counterpart construction and each in my preferred construction, as shown in full lines in 35 Fig. 1 of the drawings, provided with a central orifice and attaching margins, to which are bolted the attaching-flanges 4 and 5 of the respective portions 6 and 7 of the steam pipe 40 or main to which the separator is applied. In the construction illustrated in the drawings the upper pipe portion 6 constitutes the steam-inlet to the separator, while the lower pipe portion 7 constitutes the steam-outlet 45 therefrom.

8 is a centrally-arranged neck or tubular extension on the lower head or closure-cap 3, of a diameter approximating that of the steam-main and extending a distance up into 50 the interior of the separator-casing, so as to divide the lower portion thereof into an an-

nular receiving-chamber 9 for the water, &c., of entrainment separated from the steam in its passage through the present apparatus.

It is evident that the neck or extension 8 55 can be modified so as to curve laterally in the manner indicated in dotted lines in Fig. 1, in situations in which the steam-separator is required to be applied to an angular arrangement of such steam pipe or main. 60

10 is a drain-pipe connected to the lower end of the annular receiving-chamber 9 for the removal at any required intervals of the oil, water, &c., accumulated therein.

11 is a cylindrical casing supported axially 65 within the upper portion of the separator-casing by means of radial fins 12, fitting in recesses in the top of the main cylindrical section of the separator-casing, as illustrated in Figs. 1 and 2, and having a diameter somewhat less than the internal diameter of such separator-casing, so as to leave an annular passage between the parts, as shown in Figs. 1 and 2. Such casing is formed with an open flanged top and with a closed bottom, the central portion 13 of which is of a cone form, the marginal portion of which is curved upwardly to meet the cylindrical wall of the casing 11, while the central portion 12 is of a cone form, such construction being adapted to attain a 70 ready shedding or flow of the water, &c., toward the outlet therefor from such casing.

14 represents outlet-pipes, one or more in number, connecting with the lower end of 85 the casing 11 and extending to near the bottom of the annular receiving-chamber 9.

15 is a grid or break having a marginal flange, by means of which it is attached to the open flanged top of the casing 11. Such 90 grid is also provided with an annular depending rim 16, that is adapted to prevent in a very efficient manner the usual tendency of the oil and moisture upon the inner wall of the casing to creep in the same direction with 95 the steam as it passes back from the interior of the casing 11 into the annular passage surrounding the same. In the present invention the main central portion of the grid 11, will have a sunken form, and composed of a series 100 of circular rings 17, arranged and held in separated relation by radial bars 18, all pref-

erably cast together in one integral piece, as shown, and with a view to offer the least amount of resistance to the passage of the steam, &c., through the grid in the initial entrance thereof into the separator and, in addition, effect an efficient division or dissemination of such steam, &c., the said rings 17 and bars 18 will have a triangular shape in cross-section, with their apices in the direction of the incoming steam, &c. In the present construction the bottom of the casing 11 will have adjacent relation to the grid or break 15, as shown in Fig. 1, so as to constitute an impact wall or surface for the steam, &c., passing down through such grid, so as to insure a very perfect separation of the oil, water, &c., of entrainment carried by the steam, in that the particles of the same in the described disseminated condition will as they impact against the bottom of the casing 11 readily lose their momentum and adhere to such bottom, to be subsequently carried by gravity down into the annular receiving-chamber 9 through the drain-pipes 10.

25 No claim is made in the present application to the broad feature of a reticulated grid in combination with an impact-wall arranged in adjacent relation thereto, as the same is involved in the subject-matter of a companion application filed April 24, 1901, Serial No. 57,162.

Having thus fully described my said invention, what I claim as new, and desire to secure by Letters Patent, is—

35 1. A steam-separator, comprising in combination a vertically-arranged main casing, an inner casing having a bottom and supported centrally in the upper portion of the main casing by radial ribs, to leave an annular passage at its sides, a reticulated grid or break at the top of said inner casing, a centrally-arranged inlet-neck at the top of the main casing, an outlet-neck extending upwardly into the main casing with its opening arranged axially and in adjacent relation to the bottom of the inner casing, and a drain-pipe extending from the bottom of the inner casing to the bottom portion of the main casing, substantially as set forth.

45 2. A steam-separator, comprising in combination, a vertically-arranged main casing, an inner casing having a bottom and arranged centrally in the upper portion of the main casing to leave an annular passage at its sides, a reticulated grid or break at the top of said inner casing, a centrally-arranged inlet-neck at the top of the main casing, an outlet-neck extending axially up into the main casing with its opening in adjacent relation to the bottom of the inner casing, and a drain-pipe extending from the bottom of the inner casing to the bottom portion of the main casing, substantially as set forth.

55 3. A steam-separator, comprising in combination, a vertically-arranged cylindrical casing having upper and lower removable heads, an inner casing having a bottom and arranged

centrally in the upper portion of the main casing to leave an annular passage at its sides, a reticulated grid or break at the top 70 of said inner casing, a centrally-arranged inlet-neck at the top of the main casing, an outlet-neck extending upwardly into the main casing with its opening arranged axially and in adjacent relation to the bottom of the inner casing, and a drain-pipe extending from the bottom of the inner casing to the bottom portion of the main casing, substantially as set forth.

4. A steam-separator, comprising in combination, a vertically-arranged cylindrical casing having upper and lower removable heads, an inner casing having a bottom and supported centrally in the upper portion of the main casing by radial ribs to leave an annular passage at its sides, a reticulated grid or break at the top of said inner casing, a centrally-arranged inlet-neck at the top of the main casing, an outlet-neck extending upwardly into the main casing with its opening 85 arranged axially and in adjacent relation to the bottom of the inner casing, and a drain-pipe extending from the bottom of the inner casing to the bottom portion of the main casing, substantially as set forth.

5. A steam-separator, comprising in combination, a vertically-arranged cylindrical casing having upper and lower removable heads, an inner casing having a bottom and arranged centrally in the upper portion of the main 100 casing to leave an annular passage at its sides, a reticulated grid or break at the top of the inner casing, a centrally-arranged inlet-neck at the top of the main casing, an outlet-neck extending axially up into the main casing 105 with its opening in adjacent relation to the bottom of the inner casing, and a drain-pipe extending from the bottom of the inner casing to the bottom portion of the main casing, substantially as set forth.

6. A steam-separator, comprising in combination, a main casing having inlet and outlet necks arranged in vertical alinement, an inner casing having a closed bottom and arranged centrally in the main casing to leave 115 an annular passage at its sides, and a reticulated grid or break at the top of said inner casing, the said grid having a downward cone shape, substantially as set forth.

7. A steam-separator, comprising in combination, a main casing having inlet and outlet necks arranged in vertical alinement, an inner casing having a closed bottom and arranged centrally in the main casing to leave an annular passage at its sides, and a reticulated grid or break at the top of the inner casing, the said grid having a marginal depending entrainment-ring, substantially as set forth.

8. A steam-separator, comprising in combination, a main casing having inlet and outlet necks arranged in vertical alinement, an inner casing having a closed bottom and arranged centrally in the main casing to leave 130

65

an annular passage at its sides, and a reticulated grid or break at the top of the inner casing, the said grid having a marginal depending ring, and a downward cone shape, substantially as set forth.

5. A steam-separator, comprising in combination, a main casing having inlet and outlet necks arranged in vertical alinement, an inner casing having a closed bottom and arranged centrally in the main casing to leave an annular passage at its sides, and a reticu-

lated grid or break at the top of the inner casing, the said grid being formed by a series of bars having a triangular form in cross-section, substantially as set forth. ¹⁵

Signed at St. Louis, Missouri, this 17th day of April, 1901.

JOHN ANGELL.
